UNITED STATES PATENT OFFICE.

CHARLES G. VANDEWATER, OF AKRON, INDIANA.

REINFORCED-CONCRETE TIE.

1,082,954.

Specification of Letters Patent. Patented Dec. 23, 1913.

Application filed February 8, 1911. Serial No. 607,447.

To all whom it may concern:

Be it known that I, CHARLES G. VANDEWATER, a citizen of the United States, a resident of the town of Akron, Fulton county, State of Indiana, have invented a new and useful Improvement in Reinforced-Concrete Ties, and pray that a patent be granted therefor, of which the following is a specification.

- 10 This invention relates to reinforced concrete ties and to means for use in connection therewith whereby rails may be securely attached to the tie, one of the objects of the invention being to provide a tie and fastener which is formed in but three 15 separate parts, there being a rail fastening element integral with the tie and another rail fastening element which is shiftable relative to the tie, this last mentioned element being held in position by the weight 20 of the rail engaging the same, and by the walls of a recess within the tie within which said fastener is removably seated.

With the foregoing and other objects in view which will appear as the description proceeds, the invention resides in the combination and arrangement of parts and in the details of construction hereinafter described and claimed it being understood 25 that changes in the precise embodiment of the invention herein disclosed, can be made within the scope of what is claimed, without departing from the spirit of the invention.

30 In the accompanying drawings the preferred form of the invention has been shown.

In said drawings:—Figure 1 is a plan view of a portion of a tie having the present improvements combined therewith, a 35 portion of a rail being shown in position upon the tie. Fig. 2 is a view partly in side elevation and partly in section through a portion of a tie and showing the rail thereon, section and secured to the tie. Fig. 40 45 3 is a section on line 3—3 Fig. 2. Fig. 4 is a perspective view of the removable locking block.

Referring to the figures by characters of reference 1 designates the concrete body of the tie, the same being of any desired proportions and preferably provided with longitudinally disposed reinforcing rods 2 which may be anchored in the tie in any manner desired. The top of the tie body is formed 50 55 with a transverse channel 4 extending throughout the width of the tie body, the

width of the bottom of this channel being substantially equal to the width of the base of the rail 5 which is seated in this channel. One side of the channel has an overhanging 60 retaining wall 6 adapted to lap one side of the base flange of the rail 5 so as to thus hold the base flange seated within the channel.

A recess 7 is formed longitudinally with 65 in the top of the tie body 1 and intersects the bottom of the channel 4. That portion of the recess 7 under the channel 4 is adapted to be bridged by a wear plate 8 the ends of which are downturned as shown at 9, so 70 as to fit snugly against the sides of the tie body 1.

The means employed for locking the rail within the recess or channel 4 consists of a block 10 of the same width as the tie body 75 and which is adapted to bear snugly upon said body and to extend over the recess 7. One end of this block is so shaped as to fit snugly against the web, head and adjacent base flange of the rail 5. A tongue 11 80 extends downwardly from the block 10 and beyond the rail engaging end of the block, this tongue being so proportioned as to lie within the recess 7 with its upper edge in contact with the wear plate 8. It will be 85 noted that the lower corner of tongue 11 directly under block 10 is cut away, as at 12, so as thus to facilitate the insertion of the tongue into recess 7 when the tongue is tilted prior to placing the rail in or removing it from position in channel 4.

It is to be understood that block 10 can be of any preferred material, either of metal or concrete, the block, when formed of concrete, being provided with metallic reinforcing devices 13 embedded therein. Furthermore the tongue 11 extending from the head can also be formed of reinforced concrete or can be made of metal extending from a concrete block 10.

When it is desired to place a rail in position upon the tie, the wear plate 8 is placed in the channel 4 and one edge portion of the base of rail 5 is inserted under the overhanging wall 6. The rail, as well as the wear plate 8, is held tilted while the tongue 11 of the holding block is inserted into the recess 7. After this tongue has been properly inserted, the rail 5 can be tilted back to its proper position in the channel 4, thus forcing the tongue 11 downwardly into recess 7 and block 10 onto the top of the tie.

body 1. With the block thus positioned, its rail engaging end will act as a brace to prevent the rail from shifting laterally toward one end of the tie and will coöperate with 5 the overhanging wall 6 to prevent tilting of the rail. Furthermore as the upper edge of tongue 11 is engaged by wear plate 8 and the rail 5 bears on this wear plate, it will be seen that removal of the locking block 10 is prevented unless rail 5 is tilted upwardly and 10 inwardly so as to allow the plate 8 to be swung upwardly and thus permit tongue 11 to be withdrawn from recess 7. As all lateral pressure upon the rail, while in use, is 15 outwardly, it will be seen that there is no danger of the rail at any time tilting inwardly and elevating block 10 while the rail is in use.

What is claimed is:—

20 1. The combination with a concrete tie having a rail receiving channel extending throughout the width thereof provided with an overhanging rail engaging wall, there being a recess extending longitudinally within 25 the top of the tie and intersecting the bottom of the channel, of a locking block adapted to bear upon the tie and to bridge a portion of the recess, said block having one end adapted to engage the outer side of a rail 30 seated in the channel, and an angular tongue

extending downwardly from the block and insertible into the recess and under the seated rail, said rail constituting means, while in active position in the channel, for preventing withdrawal of the tongue from 35 the recess.

2. The combination with a concrete tie having a rail receiving channel extending throughout the width thereof provided with an overhanging rail engaging wall, there being a recess extending longitudinally within 40 the top of the tie and intersecting the bottom of the channel, of a locking block adapted to bear upon the tie and to bridge a portion of the recess, said block having one 45 end adapted to engage the outer side of a rail seated in the channel, an angular tongue extending downwardly from the block and insertible into the recess and under the seated rail, said rail constituting means, while in active position in the channel, for preventing withdrawal of the tongue from the recess, and a wear plate seated in the channel between the rail and the tongue of the locking block and having its ends engaging 55 the sides of the tie.

CHARLES G. VANDEWATER.
